ANALOG VOLTAGE TRANSLATING APPARATUS
Leslie E. Hoffman, Morton, and James S. Bowker,
Flourtown, Pa., assignors to Philco Corporation,
Philadelphia, Pa., a corporation of DelawareFiled Feb. 23, 1962, Ser. No. 175,060
4 Claims. (Cl. 340—347)

This invention relates generally to translation of analog voltages, and more particularly to translation of analog voltages by the use of current switching devices in which a common input current may be routed into either of two circuit branches.

As is well understood, an analog voltage is representative of an amplitude within an overall amplitude range which may be represented by a digit code, and it is frequently desired to convert an analog voltage to digital form, which involves comparison of the analog voltage with reference voltages that are representative of amplitude levels in said range. In one mode of translation, the analog voltage may be converted to a level-representative quantity which may then be converted to digital form. In another mode of translation the analog voltage may be converted directly to digital form.

One object of the present invention is to provide improved apparatus for translation of an analog voltage according to either of said modes.

Another object of the invention is to provide apparatus for the stated purpose which has the advantages of simplicity and high speed of operation.

Other objects of the invention will become apparent as the description proceeds.

A novel feature of the invention is the provision of apparatus comprising: a plurality of successive comparators each including a pair of circuit branches, a common current input to said branches, and means for routing the input current through one or the other of said branches depending on whether the analog voltage to be translated is less or greater than a predetermined reference voltage; means connecting one of the circuit branches of each comparator except the last to the current input of the next succeeding comparator; and an output connection extending from each of the other circuit branches.

Another novel feature of the invention is the provision of apparatus comprising: a plurality of analog-to-digital converters corresponding in number to the number of digits in a pre-selected digit code, each of said converters comprising a number of comparators corresponding to the number of changes of the digit represented by the converter, there being plural successive comparators in at least some of said converters, each of said comparators including a pair of circuit branches, a common current input to said branches, and means for routing the input current through one or the other of said branches as a result of comparison of two applied voltages; means for applying to each comparator a reference voltage representing a digit change; means for applying the analog voltage to each of said comparators for comparison with the reference voltage applied thereto; means connecting one of the circuit branches of each comparator except the last of plural comparators of a converter to the current input of the next succeeding comparator; and a voltage

2

output connection extending from each of the other circuit branches.

The invention may be fully understood from the following detailed description with reference to the accompanying drawings wherein—

5 FIG. 1 is a block diagram of apparatus according to this invention for translation of an analog voltage to a level-representative quantity;

10 FIG. 2 is a schematic illustration of two successive comparators in accordance with this invention, as employed in the apparatus of FIG. 1;

15 FIG. 3 shows a digit code according to which an analog voltage is to be converted to digital form; and

20 FIG. 4 is a block diagram of a system according to the invention for converting an analog voltage to digital form according to the digit code of FIG. 3.

25 Referring first to FIG. 1, suppose that the overall amplitude range of an analog voltage is represented by m levels each of which represents a number of a digit code. Suppose further that the reference voltages are produced each of which has an amplitude intermediate two consecutive ones of said levels. In the apparatus of FIG. 1 there are $m-1$ comparators C_1 to C_{m-1} , and there are $m-1$ reference voltages r_1 to r_{m-1} applied respectively to the comparators, for example by means of a battery 10 and a potentiometer 11. The analog voltage V from a source 12 is applied simultaneously to all of the comparators for comparison with the reference voltages. Each of the comparators has two circuit branches as hereinafter described. A constant current I is supplied to the first comparator C_1 as by means of a battery 13 and a resistor 14.

30 In operation of the apparatus shown in FIG. 1, if the analog voltage V is less than the reference voltage r_1 , the current I is routed so that an output voltage appears at output connection a_1 . However if the analog voltage V is greater than the reference voltage r_1 , current I is routed through voltage translation block T to comparator C_2 where the analog voltage V is compared with the reference voltage r_2 . If the analog voltage V is less than the reference voltage r_2 , the current is routed so that an output voltage appears at output connection a_2 . However if the analog voltage V is greater than the reference voltage r_2 , the current is routed on to the next comparator. If the analog voltage V is of such amplitude that current is routed to the final comparator C_{m-1} , the analog voltage is compared with reference voltage r_{m-1} , and an output voltage appears either at output connection a_{m-1} or a_m depending on whether the analog voltage is less or greater than the reference voltage r_{m-1} .

35 40 45 50 55 55 From the foregoing description it will be seen that in any instance an output voltage will appear at one end only one of the output connection a_1 to a_m , depending on the amplitude of the analog voltage. This output voltage may be readily converted, if desired, to the digital number which it represents, as will be well understood by those skilled in the art.

60 Referring now to FIG. 2, there are shown schematically the comparators C_1 and C_2 of FIG. 1 which are typical of any two consecutive comparators in an apparatus of the character shown in FIG. 1. Comparators C_1 comprises transistors 15 and 16 whose emitters are con-

nected to the common current input. The analog voltage is applied to the base of transistor 15, while the reference voltage r_1 is applied to the base of transistor 16. The input current I is routed through either of the circuit branches which include the transistors, according to whether the analog voltage is less or greater than the reference voltage r_1 . If the analog voltage is greater than the reference voltage r_1 the current is routed through transistor 16 to comparator C_2 via a voltage translating arrangement including in Zener diode 17 and a resistor 18. Comparator C_2 comprises transistors 19 and 20 through either of which the input current is routed depending on whether the analog voltage is less or greater than the reference voltage r_2 .

Referring now to FIG. 3, there is shown a three-digit code whose digits are designated D_1, D_2 and D_3 . It will be noted that digit D_1 changes once, digit D_2 changes twice, and digit D_3 changes four times. In converting an analog voltage to digital form according to the code shown, seven reference voltages r_1 to r_7 are utilized as hereinafter described.

FIG. 4 shows a system according to this invention for converting an analog voltage directly to digital form according to the digit code of FIG. 3. In this system there are three analog-to-digital converters 21 to 23 corresponding respectively to the digits D_1, D_2 and D_3 of the code of FIG. 3. Since digit D_1 changes only once, converter 21 comprises a single comparator 24 which is similar to one of the comparators in FIGS. 1 and 2 as above-described. Since digit D_2 changes twice, converter 22 comprises two comparators 25 and 26 and a voltage translation block 27. Since digit D_3 changes four times, converter 23 comprises four comparators 28 to 31 and three voltage translating blocks 32 to 34. Constant current I is supplied to the three converters, as by means of a battery 35 and resistors 36 to 38.

The reference voltages r_1 to r_7 as represented in FIG. 3 are supplied to the comparators from a source 39 which may comprise a battery and a potentiometer, as in FIG. 1, with seven taps on the potentiometer for deriving the seven reference voltages. The reference voltage r_4 represents the change of digit D_1 (between 0 and 1) and it is applied to comparator 24 over connection 40. Reference voltages r_2 and r_6 represent the changes of digit D_2 and they are applied respectively to comparators 25 and 26 over connections 41 and 42. Reference voltages r_1, r_3, r_5 and r_7 represent the changes of digit D_3 and they are applied respectively to comparators 28 to 31 over connections 43 to 46.

Block 47 represents any source of analog voltage which is supplied simultaneously to the comparators of the three converters over connections 48 to 50.

In operation, comparator 24 determines whether the analog voltage is less or greater than reference voltage r_4 , and an output voltage appears either at output connection 51 representing ZERO or at output connection 52 representing ONE.

Comparators 25 and 26 compare the analog voltage with reference voltages r_2 and r_6 . If the analog voltage is less than r_2 an output voltage appears at output connection 53 representing ZERO. If the analog voltage is greater than r_2 but less than r_6 an output voltage appears at output connection 54 representing ONE. If the analog voltage is greater than r_6 an output voltage appears at output connection 55 representing ZERO.

Comparators 28 to 31 compare the analog voltage with reference voltages r_1, r_3, r_5 and r_7 . If the analog voltage is less than r_1 an output voltage appears at output connection 56 representing ZERO. If the analog voltage is greater than r_1 but less than r_3 an output voltage appears at output connection 57 representing ONE. If the analog voltage is greater than r_3 but less than r_5 an output voltage appears at output connection 58 representing ONE. If the analog voltage is greater than r_5 but less than r_7 an output voltage appears at output connection 59 represent-

ing ONE. If the analog voltage is greater than r_7 an output voltage appears at output connection 60 representing ZERO.

While a system for analog-to-digital conversion according to a three-digit code has been described, it will be apparent that the invention is applicable for conversion according to other codes such as a four-digit code.

In some instances it may be desirable to equalize as far as possible the number of comparators in the converters. This can be done by rearranging the code so as to minimize the number of changes of each digit. One advantage of this is that it minimizes the "encoding time."

While the invention has been described with particular reference to the illustrated embodiments, it will be understood that the invention is not limited thereto but contemplates such modifications and further embodiments as may occur to those skilled in the art.

We claim:

1. In a system for translation of an analog voltage, the combination comprising: a first comparator comprising a pair of transistors having their emitters connected to a common current input, means for supplying constant current to said input, means for applying said analog voltage to the base of only one of said transistors, an output connection extending from the collector of said one transistor, means for applying a first reference voltage to the base of only the other of said transistors, a second comparator comprising a second pair of transistors having their emitters connected together and coupled to the collector of said other transistor, means for applying said analog voltage to the base of only one of said second pair of transistors, an output connection extending from the collector of the same transistor, means for applying a second reference voltage to the base of only the other of said second pair of transistors, and an output connection extending from the collector of the same transistor.

2. A system according to claim 1, including a Zener diode interconnecting said comparators, and a resistor having one end connected to the emitters of said second pair of transistors and having its other end connected to a voltage source.

3. In a system for translation of an analog voltage, the combination comprising: a first comparator comprising a pair of transistors having their emitters connected to a common current input, means for supplying constant current to said input, means for applying said analog voltage to the base of only one of said transistors, an output connection extending from the collector of said one transistor, means providing plural reference voltages comprising a D.C. source and a voltage divider connected in series, means for applying a first reference voltage from said divider to the base of only the other of said transistors, a second comparator comprising a second pair of transistors having their emitters connected together and coupled to the collector of said other transistor, means for applying said analog voltage to the base of only one of said second pair of transistors, an output connection extending from the collector of the same transistor, means for applying a second reference voltage from said divider to the base of only the other of said second pair of transistors, and an output connection extending from the collector of the same transistor.

4. A system for converting an analog voltage to digital form according to a binary digit code wherein each digit changes from 0 to 1 or vice versa a predetermined number of times, comprising: a plurality of analog-to-digital converters corresponding in number to the number of digits in the code, each of said converters comprising a number of comparators corresponding to the number of changes of the digit represented by the converter, each of said comparators comprising a pair of transistors having their emitters connected to a common input, there being plural successive comparators in at least some of said converters with each succeeding comparator having

its common input coupled to the collector of one of the transistors of the preceding comparator, output connections extending from all of the other collectors of the transistors constituting said converters, means for applying said analog voltage to the base of one of the transistors of each of said comparators, means for applying to the base of the other transistor of each comparator a reference voltage representing a digit change in said digit code, and means for supplying constant current to the input of each of said converters, whereby said current is routed in each converter according to the ampli-

tude of said analog voltage and an output voltage appears at one of the output connections of each converter representing the corresponding digit of the digital value of said analog voltage.
